UNITED STATES PATENT OFFICE.

HENRY KLANECKY, OF SARGENT, NEBRASKA.

GOVERNOR.

Application filed April 28, 1925. Serial No. 26,511.

This invention relates to a governor control device especially designed for use in connection with a well known type of motor vehicle, the primary object of the invention being to provide novel means for automatically moving the usual butter-fly valve to reduce the speed of the engine when the engine has been relieved of its load, and to increase the speed of the engine under a load.

Another object of the invention is to provide a device of this character which will permit the usual motor vehicle to be employed for various purposes such as grinding feed, pumping water or the like.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view illustrating the engine of a motor vehicle supplied with a controlling device constructed in accordance with the invention.

Figure 2 is a side elevational view thereof.

Figure 3 is a side elevational view of the opposite side of the engine.

Figure 4 is a sectional view through the intake manifold illustrating the butter-fly valve.

Referring to the drawing in detail, the motor is indicated generally by the reference character 5 which includes the usual fan 6 and fan pulley 7.

The device forming the essence of the invention includes a shaft 8 that carries a pulley 9 at its outer end, which pulley is adapted to frictionally engage the belt 10 forming a part of the usual motor construction to receive motion therefrom.

The shaft 8 extends through the bearing members 11 carried at the ends of the bracket member 12 which is bolted to the engine block by means of the bolts 13 that extend through arms 14 carried by the bracket member. Slidably mounted on the shaft 8 is a sleeve 15 that is formed with a groove 16 to accommodate the pins 17 carried by the forked end 18 of the rod 19 that is pivotally supported to the frame or bracket member at 20. Thus it will be seen that as the sleeve

15 is moved longitudinally of the shaft 8 the rod 19 will be moved.

This rod 19 extends laterally over the top of the engine block and downwardly as shown by Figures 1 and 2 of the drawings, the lower free end of the rod being supplied with an opening to accommodate the rod 21 that has its opposite end positioned in one of the openings 22 formed in the curved arm 23 that connects with the usual butter-fly valve 24, in such a way that movement of the rod 21 will operate the arm 23 to move the butter-fly valve.

The sleeve 15 is also formed with a groove 25 in which the heads 26 of the governor arms 27 are positioned, the arms 27 being pivotally supported at the outer ends of the arms 28 which are bolted to the member 29 which in turn is pinned to the shaft 8.

The free ends of the arms 27 are supplied with cross arms 30 and weights 31, the cross arms 30 being connected by means of coiled springs 32 so that expansion of the arms 27 is only accomplished against the tension of the coiled springs 32, which act to restrict movement of the arms.

Mounted on the inner end of the shaft 8 is a flanged member 33 in which the collar 34 moves, the collar being mounted within the curved portion 34 of the arm 35 that moves under the plate 36. Pivotally connected with the arm 35 is a relatively short arm 37 which also has connection with the controlling lever 38 so that upon movement of the controlling lever, the arm 37 will be operated to slide the shaft 8 within its bearings thereby adjusting the normal position of the shaft 8, to adjust the throw of the butter-fly valve to better adapt the device for various purposes.

Teeth 39 are formed on plate 36 and engage the lever 38 to hold the lever in various positions of adjustment.

It is to be understood that the connection between the rod 19, rod 21, arm 23 and butter-fly valve is such that the butter-fly valve is normally held in its open position, but when the governor arms move outwardly under the centrifugal force of the rotating shaft 8, the rod 19 is moved to move the butter-fly valve to reduce the quantity of fuel passing through the engine, thereby reducing the speed of the engine.

It is obvious that due to this construction, upon the slowing up of the motor, the rod is operated to allow more fuel to enter the

2
engine and compensate for the increased load.

I claim:—

1. In combination with the butter-fly valve of an internal combustion engine, an operating device embodying a bracket having bearings and adapted to be attached to a cylinder block of the engine, a shaft mounted for sliding movement and rotary movement, within the bearings, a sleeve mounted on the shaft and adapted to slide longitudinally thereof, a governor mounted on the shaft and engaging the sleeve for controlling the movement of the sleeve longitudinally of the shaft, an arm connected with the butter-fly valve, means for transmitting movement of the sleeve to the butter-fly valve to regulate the butter-fly valve, means for sliding the shaft longitudinally of the bearings to change the normal relative posi-

tions of the shaft and governor, and means for rotating the shaft.

2. In combination with the butter-fly valve of an internal combustion engine, a bracket having bearings, a shaft mounted for 25 rotary and sliding movement within the bearings, a governor controlled sleeve on the shaft, means for transmitting movement of the sleeve to the butter-fly valve to automatically control the butter-fly valve, 30 and manually controlled means for moving the shaft longitudinally of its bearings to change the normal relative positions of the sleeve and governor and means for rotating the shaft.

35
In testimony that I claim the foregoing as my own, I have hereto affixed my signature.

HENRY KLANECKY.
